US0D1002120S

(12) **United States Design Patent** (10) **Patent No.:** **US D1,002,120 S**
(45) **Date of Patent:** **** Oct. 17, 2023**

(54) **DOG TAG**

(71) Applicant: **Hangzhou Yishuo Qianxin Technology Co., Ltd**, Zhejiang (CN)

(72) Inventor: **Xiehan Zhu**, Zhejiang (CN)

(73) Assignee: **Hangzhou Yishuo Qianxin Technology Co., Ltd**

(**) Term: **15 Years**

(21) Appl. No.: **29/887,742**

(22) Filed: **Mar. 24, 2023**

(51) LOC (14) Cl. **30-08**

(52) U.S. Cl.

USPC **D30/155**

(58) **Field of Classification Search**

USPC .....
